UNITED STATES PATENT OFFICE.

FREDERIK NIELSEN, OF BOSTON, MASSACHUSETTS, ASSIGNOR, BY DIRECT AND MESNE ASSIGNMENTS, TO A. SCHREADER'S SON, INCORPORATED, OF BROOKLYN, NEW YORK, A CORPORATION OF NEW YORK.

DUST-CAP.

1,218,111.

Specification of Letters Patent.

Patented Mar. 6, 1917.

Application filed August 14, 1913. Serial No. 784,800.

To all whom it may concern:

Be it known that I, FREDERIK NIELSEN, a subject of the King of Denmark, and resident of Boston, in the county of Suffolk and 5 State of Massachusetts, have invented certain new and useful Improvements in Dust Caps, of which the following is a specification.

This invention relates to dust caps 10 adapted to be attached to vehicle wheels for inclosing inflating valves for pneumatic tires.

Of the accompanying drawings:

Figure 1 represents a section through a 15 wheel rim and through a dust cap attached thereto, an inflating valve being shown in elevation.

Fig. 2 represents an elevation of the open end of the dust cap.

Fig. 3 represents a side elevation, partly 20 in section, of the dust cap.

Fig. 4 represents a view similar to Fig. 1, showing a modified form of anchoring member secured to the wheel rim for supporting the dust cap.

Fig. 5 represents a side elevation of the anchoring member included in Fig. 4.

The same reference characters indicate the same parts wherever they occur.

A wheel rim is indicated at 10, and an inflating valve of well-known construction is indicated at 11, the valve extending through a radial hole 12 in the rim and projecting inwardly beyond the inner surface 13 of the 25 rim.

The dust cap comprises a tubular body 14 having a closed end 15 and a circular series of flexible spring tongues 16. The dust cap may be made of a single piece of ductile metal by first drawing a blank to the desired 40 shape and then sawing slots 16* to divide the open end into tongues as shown. These slots 16* do not extend into the body portion 14, but leave a continuous circular rim 17 at 45 the open end of the body portion, the tongues adjoining the periphery of said rim.

The anchoring member shown by Fig. 1 comprises a tubular body portion 18 open at both ends, a laterally extending external 50 flange 19, and an intermediate annular portion 20 connecting the flange and body portion. This anchoring member may be made

of a single piece of ductile metal. The body portion is provided with an external screw-thread 21, and is screwed into the hole 12 55 so that it is secured to the rim by its thread. The outer end of the anchoring member has a continuous circular rim which coacts with the rim 17 of the dust cap for excluding dust. The diameter of the connecting portion 20 decreases from the outer end toward the flange 19, presenting in effect an external annular flange 22. The dust cap is adapted to be attached and detached by simple longitudinal movement. The tongues form a bell 60 end, their internal surfaces having ogee curvature, as indicated at 23, for facilitating the connecting operation, and for enabling them to coact with the flange 22 to hold the rim 17 firmly against the rim at the outer 65 end of the anchoring member. The flaring of the free ends of the tongues causes flexure of the tongues away from each other while passing over the flange 22. During the attaching movement the tongues, after being 70 spread apart by the flange 22, close toward each other behind the flange, and their gripping action upon the rear side of the flange 22 keeps the rim 17 firmly against the rim of the anchoring member. When the dust cap 75 is attached, the spring tongues are slightly spread apart from their normal position by the flange 22 and hold the dust cap so firmly as to prevent rattling.

Figs. 4 and 5 show a different form of 80 anchoring member for coacting with the same dust cap. This anchoring member is formed with prongs 25 adapted to be driven into the rim 10. The prongs have converging surfaces 26 at their tips by which the 90 prongs are flexed laterally while being driven, with the result of clenching the anchoring member in the rim. This anchoring member has a flange 22* which is the full equivalent of the flange 22, and its rim 95 27 is continuous and coacts with the rim 17 when the dust cap is attached. This anchoring member is likewise made of ductile metal.

I claim:

1. A cap for a tire valve, said cap having an endless series of flexible spring portions arranged to grip a holder inserted therein.

2. A cap for a tire valve, said cap having

100

an endless series of flexible spring tongues arranged to grip a holder inserted therein, each of said tongues having an offset portion adjoining the body portion of the cap, the gripping portions of said tongues being set out from the center of the cap in consequence of said offset portions.

In testimony whereof I have affixed my signature in presence of two witnesses.

FREDERIK NIELSEN.
